UNITED STATES PATENT OFFICE.

RICHARD H. RICE, OF LYNN, MASSACHUSETTS, ASSIGNOR TO GENERAL ELECTRIC COMPANY, A CORPORATION OF NEW YORK.

ELASTIC-FLUID TURBINE.

1,093,148.

Specification of Letters Patent. Patented Apr. 14, 1914.

Application filed December 20, 1913. Serial No. 807,813.

To all whom it may concern:

Be it known that I, RICHARD H. RICE, a citizen of the United States, residing at Lynn, county of Essex, State of Massachusetts, have invented certain new and useful Improvements in Elastic-Fluid Turbines, of which the following is a specification.

This invention relates to multi-stage turbines actuated by an expansive fluid such as steam. Two classes or types of multi-stage steam turbines are now well recognized, one in which the motive fluid operates by reaction or pressure of which the Parsons machine is typical, and the other converting the steam pressure into velocity and operating by impulse or impact, as in the Curtis machine. In both types there is a drop in pressure and increase in volume as the steam progresses through the working passage of the turbine. In the Parsons machine this drop proceeds by rather small increments from one end of said passage to the other. Inasmuch as the velocity due to a given drop in pressure becomes greater and greater as the lower pressures are reached, it follows that the working passage must be correspondingly enlarged in order to permit the steam to expand and keep the same ratio between the steam velocity and the blade velocity upon which the turbine efficiency depends. This means that in a machine of the Parsons type the blades may be quite short in the high pressure and intermediate portions of the working passages, but must increase in length very rapidly in the low pressure end, and also change their curvature and increase their clearance, in order to accommodate the much greater volume of steam. Owing however, to mechanical reasons, the maximum length of the buckets is limited, so that the lowest pressure cannot be utilized to the best advantage in a Parsons turbine. Furthermore, if a larger drum is used to carry long buckets in the low pressure end, this necessitates a large balancing drum, all of which adds to the weight and the cost.

The object of my invention is to overcome these defects and obtain a greater amount of work from the energy of the low pressure steam in a turbine of the Parsons type. With this end in view, I add at the low pressure end of the machine one or more stages containing impulse wheels, each carrying preferably but a single row of buck-

ets coöperating with nozzles located in diaphragms which inclose said stages. These impulse wheels can be made of sufficient diameter to give a peripheral speed of rotation approximately correct for the best efficiency, that is to say, about one-half the speed of the steam, which in these low stages is quite high. Moreover, these impulse wheels require no balancing drums, and are much lighter in weight than blade carrying drums would be. By their use, a far greater proportion of the total energy of the steam can be turned into useful work.

In the accompanying drawing, Figure 1 is a longitudinal section of a horizontal turbine embodying my invention, and Fig. 2 is a diagram of steam pressures and volumes.

Referring first to Fig. 2, the horizontal central line represents the length of a working passage in which the steam is expanded from its initial high pressure down to absolute zero. The lines at right angles thereto represent the volumes of steam, at consecutive points along said passage, the volume being in inverse ratio to the pressure. From this figure it appears that the volume increases very rapidly and by larger and larger increments as the low pressure end of the working passage is approached so that in the final portions of said passage the volume is immensely greater than in the high pressure end. One pound of steam at 210 pounds absolute pressure occupies a volume of 2.15 cubic feet, while one pound at two pounds absolute pressure occupies 172.08 cubic feet. In order to utilize all the energy in the steam, the turbine blades should increase in length from the high pressure end of the machine to the low pressure end, in exactly the same ratio as the volume of the steam increases. In other words, the length of an ordinate of the curve x at any point represents the length of the blade at that point. It is evident that in the extreme low pressure region the blades would become so long as to give rise to dangerous vibrations, and would be too weak to withstand the centrifugal strains. Hence it is customary, in turbines of the Parsons type, to waste some energy by restricting the length of the low pressure blades to what is known to be a safe size.

In Fig. 1 I have shown a turbine having its high pressure blading 1 and intermediate blading 2 of the Parsons type. Further-

more, some of the low pressure blading 3 is of this nature, but only to the point where the length of the blades is within safe limits. Beyond that point, the turbine casing is 5 provided with one or more diaphragms 4, partitioning off one or more stages 5 in each of which is a bucket wheel 6 carrying one or more rows of buckets 7. In the dia-
10 phragm are nozzles 8 extending around the rotor and of such a shape that they convert the pressure of the steam flowing through them into velocity, though not necessarily of the diverging type; so that the wheel or wheels operate by impact, being, therefore, 15 of the Curtis type. These wheels are considerably larger in diameter than the drums so that the proper relation of vane speed to steam speed will be obtained. As many velocity stages may be used as may be found necessary to extract all the energy of the 20 steam, or at least such as can be extracted down to the lowest absolute pressure made available by a condenser. In any event, the addition of these impulse stages to the reac-
25 tion machine results in greater efficiency and economy, and makes it possible to utilize a higher vacuum.

In accordance with the provisions of the

patent statutes, I have described the principle of operation of my invention together 30 with the apparatus which I now consider to represent the best embodiment thereof; but I desire to have it understood that the apparatus shown is only illustrative, and that the invention can be carried out by 35 other means.

What I claim as new and desire to secure by Letters Patent of the United States, is:—

1. A steam turbine having a high pressure portion of the reaction type and its 40 final low pressure portion formed into one or more stages of the impact type.
2. A steam turbine having its high pressure portion of the reaction type, and its low pressure portion of the impact type. 45
3. The combination with a steam turbine of the Parsons type, of one or more low pressure stages provided with nozzles, and impulse wheels coöperating therewith.

In witness whereof, I have hereunto set 50 my hand this sixteenth day of December 1913.

RICHARD H. RICE.
